UNITED STATES PATENT OFFICE.

LUDWIG HOCHSTEIN, OF DIETRICHSDORF, GERMANY.

ASH-EJECTOR.

SPECIFICATION forming part of Letters Patent No. 716,418, dated December 23, 1902.

Application filed May 13, 1902. Serial No. 107,110. (No model.)

To all whom it may concern:

Be it known that I, LUGWIG HOCHSTEIN, a subject of the Emperor of Germany, whose post-office address is Katherinenstrasse 14, 5 Dietrichsdorf, near Kiel, Germany, have invented certain new and useful Improvements in or Connected with Ash-Ejectors; and I do hereby declare the following to be a full, clear, and exact description of the invention, such 10 as will enable others skilled in the art to which it appertains to make and use the same.

In connection with ash-ejectors as hitherto employed for discharging ashes from ships and the like it has been found that inconveniences arise in tending them, as jolting and shaking occur in the pressure-pipe when the ash-ejector is started, and in consequence of the slight pressure at starting the ash-ejector fails to act when the nozzle-pipe is opened. 15 Moreover, several persons are always required to look after the ejector.

By means of the apparatus that forms the object of the present invention the working is simplified and the above-named difficulties 20 are obviated. The apparatus enables the pump to work continuously independently of the ash-ejector being in action or not. The pump-piping is divided into two parts by the introduction therein of suitable reversing-organs, so that the one pipe leads to the ash-ejector, the other to the outside or some other suitable place. This reversing action may be effected either by the direct or indirect 25 movement of the reversing-organs. Contrivances for indirect reversing are illustrated in Figures 1 to 6 and for direct reversing in Figs. 7 to 10. Compared with those for indirect reversing the direct-reversing contrivances have the disadvantage of involving a large expenditure of power. This kind of apparatus is suitably composed of a valve-cone body furnished with double valve-cones, one of which cones closes the nozzle-pipe leading to the ash-ejector, the other closing a second nozzle-pipe, 30 leading to the outside. The reversing of these valve-cones can be effected by the actual valve-body being formed as a differential piston or as a single piston, the water under pressure being conveyed either onto the one 35 or the other end of the piston. The shutting-off organs (valve-cones, cocks, and valves) of the two pipes may also be placed wide apart

from one another, in which case the one organ is applied to the ash-ejector, the other to the pump or at some other spot. The principal effect of such a device is that after the ejector-nozzle pipe has been opened the pressure of water necessary for the working can at once enter; further, that after the pressure-pump has been started all further attention is rendered unnecessary and stoppage or overrunning of the pump and consequent jolting and shaking in the pressure-pipe itself avoided.

In the accompanying drawings, Figs. 1 to 6 represent indirect-switching devices, Figs. 1 and 2 the construction of the valve-cone body as a differential piston, Fig. 1 showing the smaller piston shut off from the discharging-chamber and receiving the water under pressure through special openings, whereas in Fig. 2 the said piston is shown as being directly in the discharging-chamber. Fig. 3 illustrates the employment of an ordinary piston, the water under pressure being conveyed to each side of the piston by special conduits. Figs. 4, 5, and 6, which relate to Figs. 1, 2, and 3, represent different positions of the distribution-cock. Fig. 7 shows the employment of two valves, Figs. 8 to 10 the employment of 80 a three-way cock.

The arrangement of the reversing-organs is as follows: The nozzle-pipe *b*, Fig. 1, leads to the ash-ejector, the nozzle-pipe *c* to the discharge-pipe. Both are closed by the cones *k* and *z*, connected with the differential piston *s r*. The valve-cone body is hollow, and its interior communicates, by holes *d* and *f*, with the supply-pipe *e* or chamber *l*. The differential piston, Fig. 1, consists of the larger piston *s* and the smaller piston *r*, to the latter of which the water under pressure is conveyed through openings *g*. For reversing purposes the cock *a* is employed. If the cock be turned into the position indicated in Fig. 1, the water flows from the chamber *e* through the passage *p* and the cock *a* over the larger piston *s* of the differential piston, and in consequence of the considerable difference of surface between the surface of the larger piston and that of the smaller piston causes the differential piston *s r* to descend, the cone *k* being removed from the nozzle-pipe *b*—that is to say, opens the pipe and closes the nozzle-pipe

c. The consequence is that the stream of water from *e* flows to the ash-ejector and the work of the ejector begins. If the cock *a* now be turned to the extent of ninety degrees, Fig. 4, the surface of the piston *s* will be brought into communication with the external atmosphere—that is, will be relieved of pressure—while the smaller piston *r*, which is held continuously under water-pressure by the water reaching it through openings *d* *g*, must now move in opposition to the differential piston, so that the nozzle-pipe *b* is closed. The water under pressure will now pass through *d* *l* and the nozzle-pipe *c* to the discharge-pipe as long as the cock *a* is closed, whence it is clear that the pressure-pump remains continuously in action quite independently of the ash-ejector—that is, it requires no special attention.

The arrangement illustrated in Fig. 2 differs from that shown in Fig. 1 only by the circumstance that the smaller differential piston *r* projects directly into the discharge-chamber *l*. The action is the same as in Fig. 1. The second position of the cock *a* is shown in Fig. 5.

In the arrangement with a single piston (shown in Fig. 3) the water under pressure is conveyed to the different surfaces of the piston only through the openings *d* *f*, and in this case the cock *a* is furnished with two ways, one of which effects a communication of the pressure-chamber *l* with the one side of the piston and the other a communication of the opposite side of the piston with the atmosphere. The cock *a*, as shown in Fig. 3, is in the position in which the top of the piston is in communication with the atmosphere, the bottom with the pressure-chamber *l*. The action will at once be seen from the drawing. The upper and lower surfaces of the piston are alike.

According to Fig. 7, two valves *v* are inserted in the pressure-pipe of the pump, which must be simultaneously operated, so that the one is opened, whereas the other is closed. Quick-closing valves are desirable, but instead of these cocks may be put in. In this case also the pipes to the ash-ejector and to the outside are alternately opened or closed.

In Fig. 8 the pressure-pipe of the pump is provided with an ordinary three-way cock *w*, and when the plug is in the position shown in Fig. 9 the water is conveyed to the ash-ejector, while when the plug is in the position shown in Fig. 10 it is conveyed to the outside.

In the single-piston arrangement shown in Fig. 3 the water under pressure is conveyed partly through *h* and partly to the different piston-surfaces only through the openings *d* *f*, and in this case the cock *a* is furnished with two ways, of which the one, *t*, forms the communication of the pressure-chamber *l* with the one side of the piston, the other, *p*, the communication of the opposite side of the piston with the atmosphere. In Fig. 3 the cock *a* is in the position in which the top of the piston

is in communication with the atmosphere, the bottom with the pressure-chamber *l*. In Fig. 6 the position of the cock *a* is reversed. It is obvious that the water under pressure flowing through *d* *f* collects in the chamber *l*, flows partly away through *h*, and partially exerts pressure on the lower or upper surface of the piston *o*, according to the position of the cock *a*. The piston-surfaces are alike above and below.

The chief feature of the invention consists in the avoidance of the joltings and shakings which formerly occurred and in the ability to work the whole apparatus with only a single attendant.

What I claim, and desire to secure by Letters Patent, is—

1. An apparatus for permitting the pumps of ash-ejectors to be kept in continuous action comprising in combination: two valve-seats; a valve-cone adapted to close each valve-seat; a tube connecting said valve-cones and having openings near each valve-cone; a piston-body mounted on said tube; a chamber inclosing said piston-body; a chamber inclosing each end of said tube; a pressure-main connected with one of the chambers surrounding the ends of said tube; channels connecting one surface of said piston with the chamber connected with said pressure-main and with the atmosphere; and a cock adapted to open and close said channels according to desire; substantially as set forth. 100

2. An apparatus for permitting the pumps of ash-ejectors to be kept in continuous action, comprising in combination: a pressure-main; two valve-seats in communication with said pressure-main; valve-bodies adapted to close said valve-seats; and means to simultaneously shut one valve when the other is opened; substantially as, and for the purpose, set forth. 105

3. An apparatus for permitting the pumps of ash-ejectors to be kept in continuous action, comprising in combination: two valve-seats; a valve-cone adapted to close each valve-seat; a tube connecting said valve-cones and having openings near the middle and approximate to said valve-cones; a differential piston mounted on said tube with the smaller piston-surface adjacent to the openings near the middle of said tube; a chamber inclosing said piston-body; a chamber inclosing each end of said tube; a pressure-main connected with one of said chambers surrounding the ends of said tube; channels connecting one surface of said piston with the chamber connected with said pressure-main and with the atmosphere; and a cock adapted to control said channels; substantially as, and for the purpose, set forth. 110 115 120 125

4. An apparatus for permitting the pumps of ash-ejectors to be kept in continuous action, comprising in combination: a chamber connected to the pressure-main of the pump; a valve in said chamber adapted to close the ejector-opening therein; a conduit commu- 130

nicating with said chamber; a second valve adapted to close said conduit, means to keep said first valve normally closed and said second valve normally open under the action of
5 the water-pressure to open said first valve and simultaneously close said second valve when desired; substantially as set forth.

In testimony whereof I affix my signature in presence of two witnesses.

LUDWIG HOCHSTEIN.
